UNITED STATES PATENT OFFICE.

MELVIN L. STONE, OF LOWELL, MASSACHUSETTS, ASSIGNOR TO DRAPER COMPANY, OF HOPEDALE, MASSACHUSETTS, A CORPORATION OF MAINE.

AUTOMATIC WEFT-REPLENISHING MECHANISM FOR LOOMS.

No. 905,245.

Specification of Letters Patent.

Patented Dec. 1, 1908.

Application filed November 28, 1905. Serial No. 286,437.

To all whom it may concern:

Be it known that I, MELVIN L. STONE, of Lowell, Middlesex county, Massachusetts, have invented certain new and useful Improvements in Automatic Weft-Replenishing Mechanism for Looms, of which the following is a specification.

The present improvements relate to the construction of the hopper or magazine which contains a supply of spare weft-carriers to be fed automatically one by one into weaving position in the loom, as the condition of the working weft requires, and to the means for taking care of the loose threads during the occupancy of the magazine by the weft-carriers, and as each weft-carrier is transferred into weaving position; and one embodiment thereof is illustrated in the accompanying drawings, wherein:

Figure 1, is a plan view of the weft-replenishing mechanism. Fig. 2 is a side view of the mechanism. Fig. 3 is a cross-section of the magazine in the plane indicated by the line 3—3 in Fig. 2. Fig. 4, is a longitudinal section in the plane indicated by the line 4—4, in Fig. 1. Fig. 5, is a detail section of the traveling thread-holder.

The present improvements may be incorporated in any loom having transferring mechanism capable of automatically transferring a spare weft-carrier into weaving position in the loom whenever the condition of the working weft so demands. There is shown in the drawings a pivoted transferrer A, well-known for this purpose and for cooperation with weft-carriers, such as the illustrated bobbins B, B, which are capacitated to be automatically inserted into the shuttle on the lay when the running weft breaks, runs out, approaches exhaustion, or otherwise requires replenishing. The weft-carriers are, in accordance with the present invention, supported by a stationary magazine C, fixed to a bracket D, which is carried by any stationary part of the loom, such as one end of the breast-beam.

Coöoperating with the transferrer and the magazine are a usual fixed stop E, and spring upheld finger F, which support in correct position the butt of the weft-carrier which is next to be transferred into weaving position. The yielding finger F, is pivoted at a, on fixed stud carried by the magazine, and it is normally upheld by a spring c, en-

circling a pin d, fixed on an arm e, fast with the finger F, said spring bearing against a stationary lug f, fixed to the magazine. When the transferrer A, descends to transfer the lowest weft-carrier B, into weaving position, the finger F, yields to allow the descent of the supported weft-carrier and then immediately ascends in time to support the next succeeding spare weft-carrier.

The magazine is of a length to hold any desired number of weft-carriers, and is of the type wherein the weft-carriers feed by gravity. As shown, the magazine is inclined, and is broken away at the middle to indicate its permissible variable length. The inclination of the magazine permits the weft carriers to descend by gravity, and within a given reachable height affords a maximum weft-carrier holding capacity. The bottom G, of the magazine preferably supports the weft-carriers throughout their length. Near its lower end the magazine has a fixed top hood H, covering the length of the weft-carriers but separated at its outer end from the bottom to provide a free passage g, for the threads. Above the hood is a swinging cover I, which incloses the butts of the remainder of the stack of spare weft-carriers. The bottom, hood and cover are furnished with longitudinal ribs b, b, to supply a retaining guide channel for the butts of the weft-carriers. The magazine, thus constituted, is open at the lower end to permit the successive discharge of the weft-carriers as the transferrer acts; the stack of weft-carriers being normally supported by the stop E, yielding finger F, and by the usual yielding tip-supporting finger J. The magazine is also open at the top to admit insertion of spare weft-carriers. By swinging up the cover I, however, the magazine may be quickly filled when empty.

The loose weft-ends or threads of the several weft-carriers are all attached to an endless flexible traveling thread-holder. The holder, as shown, is an endless flexible band K, (conveniently of thin sheet metal) having holes re-inforced by eyelets i, i, which coöperate with the teeth of a driving sprocket wheel L. This endless holder is supported by two guide pulleys, M, M, which are rotatively mounted on rods N, projecting from the magazine. The holder has riveted

to it, throughout its length, equally spaced thread studs O, one of which is in register with each of the weft-carriers in the magazine. When the weft-carriers are placed in the magazine the loose thread of each is secured to the corresponding registering stud O.

As each weft-carrier is transferred into weaving position the traveling thread-holder K is automatically advanced one step so that the studs O, keep pace with their weft-carriers, and, hence, each stud is always in register with its weft-carrier when the transfer takes place. To this end, the sprocket wheel L, is carried by a shaft P, journaled beneath the magazine, and said shaft has at its inner end a ratchet wheel Q, and a star wheel R. A pawl S, pivoted at m, to the arm e, of finger F, engages the ratchet wheel R, so that as said finger is swung at each transfer the ratchet Q is turned one step, and the flexible traveling thread-holder is advanced the proper distance.

25 A detent roll T, (carried by lever U, pivoted at t, to the magazine and pulled upon by spring V,) engages the star wheel R, and insures the exact advance of the thread-holder and the maintenance of its position between successive advances.

Owing to this organization, the weft-carriers are fed by gravity, and there can be no unwinding or entanglement of the threads because their holder is automatically advanced as the weft-carriers drop.

The magazine extends rearwardly and upwardly from the breast-beam and towards the back of the loom. Its open mouth is near the back of the loom and still low enough to be readily reached by an attendant from behind the loom. An important advantage of this is that the magazine can be filled by a helper passing along the usual aisle between the backs of adjacent rows of 45 looms where he is wholly out of the way of the weaver.

I claim as my invention:—

1. An automatic weft-replenishing loom, having, in combination, a magazine in which the weft-carriers feed by gravity, a trans- 50 ferrer for feeding the weft-carriers one by one into weaving position in the loom, an endless traveling flexible thread-holder having a plurality of devices for separately holding the threads of all the weft-carriers 55 in the magazine and automatic actuating instrumentalities for moving said holder one step whenever the transerrer acts.

2. An automatic weft-replenishing loom having, in combination, a magazine for weft- 60 carriers, a traveling thread-holder movable independently of said magazine and actuating instrumentalities for moving said thread-holder automatically as the weft-carriers advance.

3. An automatic weft-replenishing loom, having, in combination, a magazine for weft- 70 carriers, and a traveling thread-holder movable independently of the magazine and having a plurality of devices for separately holding the threads of the several weft-carriers in the magazine.

4. An automatic weft-replenishing loom having a magazine with a bottom support for weft-carriers and a swinging cover extending over the butts of the supported weft-carriers and cooperating with said bottom to supply a guide-way for said carriers.

5. An automatic weft-replenishing loom having a stationary magazine mounted on a 80 support in front of the bay and extending upwardly and rearwardly from bottom to top, the upper rear end of the magazine being back of the bay and extending sufficiently to the rear to enable access thereto for re- 85 filling by a person standing back of the loom.

In testimony whereof I affix my signature in presence of two witnesses.

MELVIN L. STONE.
